(57) **CLAIM**

The ornamental design for a sock stretcher device, as shown and described.

DESCRIPTION

FIG. 1 is a top view of the sock stretcher device showing the stretch tubes in position for installing a sock;

FIG. 2 is an end view of the sock stretcher device as viewed from the operating handle end showing the leverage handles in position for installing a sock;

FIG. 3 is a side view of the sock stretcher device as viewed from one side. The opposite side is a mirror image;

FIG. 4 is a perspective view of the sock stretcher device as viewed from the leverage handles end. The broken lines shown are for illustrative purposes only and form no part of the claimed design;

FIG. 5 is a perspective view of the sock stretcher device as viewed from one side of the stretch tubes. The opposite side is a mirror image. This view shows the leverage handles placing the stretch tubes in position to install a sock; and,

FIG. 6 is a perspective view of the sock stretcher device as viewed from the leverage handles end. This view shows the operating handles in position to stretch a sock on the stretch tubes. The broken lines shown are for illustrative purposes only and form no part of the claimed design.
